To all whom it may concern:

Be it known that I, David Rosenthal, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The horizontal lines at the front neckline portion of the dress represent folds, which do not extend to the back.

The shaded area at the central collar portion in the rear, represents a zipper fastener.

I claim:

The ornamental design for a dress, substantially as shown and described.

DAVID ROSENTHAL.
